(57) **CLAIM**

The ornamental design for a spinal disc implant with conic protrusions, as shown and described.

DESCRIPTION

FIG. 1 is a perspective view of a spinal disc implant with conic protrusions, showing our new design;

FIG. 2 is a side elevation view thereof;

FIG. 3 is a top plan elevation view thereof;

FIG. 4 is a side elevation view of an alternate embodiment thereof; and,

FIG. 5 is a perspective view of an alternate embodiment thereof.

1 Claim, 1 Drawing Sheet

FIG. 1

FIG. 2

FIG. 3

FIG. 4

FIG. 5
